UNITED STATES PATENT OFFICE.

GEORGE NEVENS, OF BRUNSWICK, MAINE.

GUARD-RAIL.

SPECIFICATION forming part of Letters Patent No. 380,587, dated April 3, 1888.

Application filed January 12, 1888. Serial No. 260,528. (No model.)

To all whom it may concern:

Be it known that I, GEORGE NEVENS, a citizen of the United States, residing at Brunswick, in the county of Cumberland and State 5 of Maine, have invented certain new and useful Improvements in Guard-Rails for Frogs, Switches, &c.; and I do hereby declare the following to be a full, clear, and exact description of the invention, such as will enable others skilled in the art to which it appertains to make and use the same.

My invention relates to guard-rails to be used on railway-tracks at frogs, switches, bridges, and the like. The guard-rail hitherto in use has consisted of a slightly-curved rail spiked to the ties on the inside of the main rail, its ends being more distant therefrom than its central portion. The flanges of the wheels striking continually against the convex portion of the upper flange of the guard-rail had a constant tendency to roll the rail inward toward the center of the track, the height of the rail furnishing a leverage whereby the spikes were loosened and pulled out. For this reason it has always been exceedingly difficult to keep guard-rails spiked in place, and constant care has been necessary to prevent the spikes from pulling out and the rail from being displaced, thus resulting 25 in great annoyance and danger. This has been particularly true in the matter of guard-rails for frogs where the flange of the wheel comes in contact with the guard-rail at nearly every passage of a train. Another difficulty 30 with the old guard-rails has been that, being secured by spikes to every tie, they have had no elasticity, and have consequently caused much roughness in the running of trains over frogs, switches, &c.

40 My invention consists of a guard-rail having the web and the upper flange removed from its ends and the lower flange turned at right angles and formed to be hooked over or otherwise secured to the lower flange of the main rail.

It further consists of the combination, with the above, of a link adapted to clasp the lower flanges of both rails at intermediate points.

I illustrate my invention in the accompanying drawings, in which—

Figure 1 represents a plan of a railway-frog and its guard-rail. Fig. 2 shows a section through *xx* of Fig. 1. Fig. 3 shows a section through *yy* of Fig. 1.

A is the frog, and *B* the opposite main rail.

D shows my improved guard-rail. The web and upper flange are removed for a short distance from each end, and the lower flange is 60 bent horizontally at right angles, or nearly so, and forms an offset, *D*, the end of which offset is turned up at *D*'' to form a hook. As thus formed the ends *D*'' are hooked over the outer edge of the lower flange of the main rail, the 65 offset passing below the main rail.

The guard-rail is steadied in place by spikes. It will be seen that by this construction the rail is effectually prevented from rolling inward under the pressure of the wheels 70 upon its upper flange, and it is impossible for it to work out of place without actually breaking.

When the flanges of the wheel strike the guard-rail, the latter yields slightly, owing to 75 its elasticity, thus making the motion of the car over the frog much more easy than it otherwise would be.

In most cases I prefer to re-enforce my device by one or more links, *C*, which are 80 clasped over the lower flanges of the guard-rail and the main rail intermediate between the two ends of the former. When the guard-rail is long, a number of these links will be necessary.

I do not wish to limit myself to an offset bent at right angles, or nearly so; but I consider this the most simple and preferable construction. The offset could be bent to make any angle with the guard-rail.

I claim—

1. A guard-rail having the lower flange at each end extended and bent horizontally outward and adapted to be secured to the lower flange of the main rail, substantially as shown. 95

2. A guard-rail having its lower flange at each end extended and bent horizontally outward and adapted to be hooked over the outer

edge of the lower flange of the main rail, substantially as shown.

3. A guard-rail having the lower flange at each end extended and bent horizontally outward and connected with the main rail, in combination with a link for clasping the lower flanges of the main and guard rails, substantially as shown.

In testimony whereof I affix my signature in presence of two witnesses.

GEORGE NEVENS.
